UNITED STATES PATENT OFFICE.

CLARK L. VARNER, OF SURREY, CALIFORNIA, ASSIGNOR OF ONE-HALF TO W. W. VARNER, OF SANTA PAULA, CALIFORNIA.

TOY.

No. 858,689.

Specification of Letters Patent.

Patented July 2, 1907.

Application filed August 10, 1906. Serial No. 329,974.

To all whom it may concern:

Be it known that I, CLARK L. VARNER, a citizen of the United States, residing at Surrey, in the county of Los Angeles and State of California, have invented new and useful Improvements in Toys, of which the following is a specification.

My invention relates to a new and amusing toy in which projecting mechanism is used to discharge a parachute into the air to a considerable height, which upon reaching the limit of its flight will open and descend slowly. I accomplish this object by means of the device described herein and illustrated in the accompanying drawings in which:

Figure 1—is a side elevation of the gun with the parts broken away to more clearly disclose the projecting mechanism and with the parachute in place therein in its closed position. Fig. 2—is a side elevation of the parachute in its open position. Fig. 3—is an enlarged sectional detail showing the manner of attaching the inner ends of the parachute ribs. Fig. 4—is an enlarged sectional detail of the runner showing the method of attaching the stretcher ribs thereto.

Referring to the drawings 5 indicates a toy gun which has a bore 6 and a slot 7 on the under side thereof which 25 communicates with the inner end of the bore 6. Pivotally mounted in this slot 7 is a trigger 8, the inner portion of which forms a dog 9 which engages a notch 10 in the end of the spring controlled plunger 11.

On either side of the barrel of the gun are transverse 30 slots 12 which extend from the inner end of the bore 6 to within a short distance of the outer end. A pin 11 transversely secured in the plunger 11 projects into these slots which form guide ways for the plunger so that the notch 10 will always engage the dog on the end of the trigger when the plunger is pulled rearwardly. A 35 spring 13, one end of which is secured to the under side of the barrel and the other end to the trigger below its pivotal point always keeps the dog in such a position so that the dog will always engage the notch 10 when the plunger is pulled rearwardly. The plunger is controlled by coiled springs 14, the outer ends of which are secured to eyes 15 which are secured to the sides of the barrel. The inner ends of these springs are secured to the ends of the pin 11 secured to the plunger 11.

45 The parachute 16 is preferably constructed with a cylindrical rod 17 having a weight 18 on its outer end so that when descending it will hold the parachute in a vertical position. The upper end of the rod 17 has a

fitting 19 to which are pivotally attached ribs 20. To the outer ends of these ribs 20 is secured a cover 21 of any suitable fabric, preferably of silk as that fabric is the strongest and lightest. Slidably mounted on the parachute rod 17 is a runner 22 to which are pivotally attached stretcher rods 23, the other end of these rods are bifurcated and pivotally attached to ribs 20. Stop 55 22 on rod 17 limits the upward movement of runner 22 and a spring catch 24 is secured to the rod 17 so as to hold the runner 22 stationary when the parachute is in its open position. A number of flexible strips 25 are secured to the fitting 19 and the ribs 20. These strips 60 are for the purpose of keeping the parachute slightly open, so that when it begins to descend after being ejected from the gun the air will enter and inflate it.

In the operation of this device the plunger 11 is pulled rearwardly until the notch engages the dog on the end 65 of the trigger. The parachute in its closed position is then inserted in the bore 6 ready for ejection. After the parachute has reached the upward limit of its flight the air causes the falling parachute to open and if descends slowly and gracefully to the ground, the 70 weighted end of the rod 17 always keeping the parachute in its vertical position.

Having described my invention what I claim as new and desire to secure by Letters Patent is:

1. A parachute, comprising a centrally disposed rod 75 weighted on its lower end; of a plurality of ribs pivotally secured to the upper end of said rod, said ribs extending when in their operative position above the upper end of said central rod; a flexible covering unconnected to the rod but having its edge secured to the outer ends of said ribs; a runner slidably mounted on said rod; a plurality of stretcher rods pivotally secured to said ribs and to said runner; and means secured to said rod, whereby the runner is securely held from movement when the parachute is in an opened position.

2. A parachute, comprising a central cylindrical rod weighted on its lower end; ribs pivotally secured to its upper end; a runner slidably mounted on said rod; stretcher ribs pivotally attached to said runner and to said first named ribs; a flexible covering secured to the outer end of said first named ribs; and flexible means secured to said central rod and to the outer end of said first named ribs to retain the parachute in a partially open position when in its inoperative position.

In witness that I claim the foregoing I have hereunto 95 subscribed my name this 2nd day of August, 1906.

CLARK L. VARNER.
